US00D865722S

(12) **United States Design Patent** (10) **Patent No.:** **US D865,722 S**
(45) **Date of Patent:** **** Nov. 5, 2019**

(54) **EARPHONE**

(71) Applicant: **GUANGZHOU LANSHIDUN ELECTRONIC LIMITED COMPANY**, Guangzhou (CN)

(72) Inventor: **Hejin Cai**, Guangzhou (CN)

(73) Assignee: **GUANGZHOU LANSHIDUN ELECTRONIC LIMITED COMPANY**, Guangzhou (CN)

(**) Term: **15 Years**

(21) Appl. No.: **29/703,004**

(22) Filed: **Aug. 23, 2019**

(51) **LOC (12) Cl.** **14-01**

(52) **U.S. Cl.**

USPC **D14/223**

(58) **Field of Classification Search**

USPC D14/223; D24/174; 128/864, 865, 866; 181/129, 130, 135; 379/430, 431; 381/380, 381, 324, 322; 455/90.3, 575.1, 455/569.1

CPC H04R 1/10; H04R 1/1066; H04R 1/1016; H04R 5/033; H04R 5/0335; H04R 25/00

(57) **CLAIM**

The ornamental design for an earphone, as shown and described.

DESCRIPTION

FIG. 1 is a perspective view of an earphone shown my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines in the drawings depict portions of the earphone that form no part of the claimed design.

1 Claim, 9 Drawing Sheets
